UNITED STATES PATENT OFFICE.

GEORGE H. PUTNAM, OF SOUTH BOSTON, MASSACHUSETTS.

CAR-COUPING.

1,155,683.

Specification of Letters Patent.

Patented Oct. 5, 1915.

Application filed April 22, 1913. Serial No. 762,809.

To all whom it may concern:

Be it known that I, GEORGE H. PUTNAM, of South Boston, in the county of Suffolk and State of Massachusetts, have invented 5 certain new and useful Improvements in Car-Couplings, of which the following is a specification.

This invention relates to devices for coupling cars and has, for its underlying principles, automatic action and interchangeability of parts.

In the ordinary styles of coupling devices now in use, there is more or less danger of accidents by reason of the fact that pins or 15 bars must be inserted by hand at the moment the cars come together.

My coupling mechanism comprises what I call a male and a female component which will automatically enter into locking engagement with each other when they are placed 20 in alinement and the cars are brought together. When holding these parts in alinement, the operator's hands and body are so positioned that it is impossible for him to 25 get squeezed or jammed. In my preferred form, which is illustrated in the accompanying drawings, I provide two female members which are exact duplicates of each other, and one male member, although but one of 30 each may be used without departing from the spirit of my invention, as will be later described. By using the three parts above mentioned, a car equipped with my device may be shackled with any other which is 35 provided with the ordinary draw-bar, by removing the desired parts from the end not in use and transferring them to the second car. This feature will be more fully explained later.

40 In the drawings, which form part of this specification,—Figure 1 is a side elevation, partly in section, of my complete device in use on two ordinary draw-bars. Fig. 2 is a section on line 2—2 of Fig. 1, with the parts 45 locked. Fig. 3 is a similar section, unlocked. Fig. 4 is a plan view, partly in section, of Fig. 1. Fig. 5 is a detail showing the adaptation of my coupler for use with an ordinary draw-bar.

50 My, so-called, female members are marked 1 and are shown mounted on the usual draw-bars 2 and held in place by pins 3. The forward ends of members 1 are recessed at 4 to receive the male member 5. Member 5 55 is double-ended and is provided with an annular groove 6 near each end which is adapt-

ed for engagement with a locking-plate 7, pivotally mounted on member 1 at 8, and held in locking position by the spring 9, the latter being secured at one end to the member 1, and having a free end adapted to engage a boss or surface 10 formed within the opening in member 1 through which locking-plate 7 is designed to play. Both ends of member 5 are tapered, as shown at 11, so 60 they will engage the locking-plates 7 upon entering the chambers 4, and automatically raise them until grooves 6 are in register therewith, when springs 9, aided by gravity, will insure engagement of grooves 6 by locking-plates 7. To unlock or uncouple the cars, a ring 12, attached to the free, projecting end of locking-plate 7, is lifted, as in Fig. 3, against the action of spring 9, to bring the plate 7 out of engagement with 70 the groove 6, whereupon the cars are free to draw apart.

From the foregoing, it will be noticed that but one locking-plate 7 is operated for uncoupling, and consequently, but one female member is essential, as the member 5 80 could be formed integral with the opposite draw-bar 2.

I prefer to use two members 1 for the convenience of shackling cars which are 85 equipped only with the ordinary draw-bars 2. In this case, one will be placed on each adjacent draw-bar, the member 5 will be inserted and locked in one of them, and as the cars are brought together, the opposite 90 member 1 is held in alinement with the member 5, which will automatically raise locking-plate 7 by reason of the beveled end 11, and when it has entered opening 4 sufficiently to permit engagement of plate 7 95 with groove 6, this engagement will automatically take place.

In uncoupling, either locking-plate 7 may be released and the operator's hand need never occupy a dangerous position.

100 I do not limit myself to the specific form illustrated.

What I claim is:—

1. A car-coupler comprising a recessed member and a lock-pin adapted to enter 105 into, substantially, rigid locking engagement with each other; in combination with a latch, pivotally mounted at the top of said member, and housed entirely within the same, a free end on said latch adapted for 110 projection through an opening in the side of said member, said latch being so designed

as to automatically engage and lock said pin, and an opening through the side of said member adapted for the projection therethrough of said free end, said opening being 5 designed to limit the pivotal action of said latch.

2. A car-coupler comprising a recessed member adapted to be rigidly mounted on the draw-bar of a car, and a lock-pin adapted 10 to be rigidly connected to the draw-bar of an adjacent car to be shackled; in combination with a rounded boss formed integral with said member, a latch formed with a curved hook at one end, said hook being designed 15 to form a pivotal connection with said boss, means whereby the middle portion of said latch may automatically engage and lock said pin, means whereby said pin may enter into rigid locking engagement with 20 said member, and means, attached to the free end of said latch, for releasing its engagement with said pin.

3. A car-coupler comprising a recessed member and a lock-pin adapted to enter into 25 engagement with each other; in combination

with a rounded boss formed integral with said member, a latch formed with a curved hook at one end which is adapted to pivotally engage said boss, means whereby said latch may automatically lock said pin in 30 such engagement, and means, attached to the free end of said latch, for releasing said lock.

4. A car-coupler comprising a recessed member and a lock-pin adapted to enter 35 into, substantially, rigid engagement with each other; in combination with a rounded boss formed integral with said member, a latch, housed within said member, and adapted to automatically lock said pin in 40 such rigid engagement, and a curved hook, on said latch, adapted to pivotally engage with said boss.

In testimony whereof I have affixed my signature, in presence of two witnesses.

GEORGE H. PUTNAM.
